TENSIOMETER

Eric A. Black, Red Bank, N.J.

Application November 13, 1945, Serial No. 628,343

9 Claims. (Cl. 73--143)

(Granted under the act of March 3, 1883, as
amended April 30, 1928, 370 O. G. 757)

1

The invention described herein may be manufactured and used by or for the Government for governmental purposes, without the payment to me of any royalty thereon.

The present invention relates to tensiometers and more particularly to tensiometers which are well adapted for use with guys as used for staying radio antenna towers and the like.

In adjusting the tension on guys, the usual practice has been either to test the tension by touch, which of course is highly unsatisfactory, or by using some complicated and expensive tensioning mechanism, which in some instances requires more than a single anchorage for each guy.

It is therefore an object of the present invention to provide a tensiometer which is simple and inexpensive to manufacture and which may be installed permanently with a guy, so that it is not necessary to open the guy to insert a tensiometer at the time of testing and so that the guy tension may be periodically adjusted without the use of additional apparatus.

It is a further object to provide a tensiometer which may be readily set for a predetermined amount of tension so that its use in the field is simple and rapid.

It is a still further object to provide such a tensiometer wherein any of the parts which might be adversely affected by the elements, may be removed once the desired tension has been set up and they may be readily reinstalled and the tensiometer reused subsequently as desired.

These and other objects and advantages of my present invention, which will be better understood as the detailed description thereof progresses, are obtained in the following manner.

I provide a tensiometer which is interposed into a guy at any convenient point, the guy being separated at that point so as to provide two free ends to which the tensiometer may be fastened. The tensiometer includes a lever beam which is positioned transversely to the axis of the guy. The free end of one portion of the guy is suitably secured to the fulcrum point of the lever beam which is near one end thereof, and the free end of the second portion of the guy is secured to the said lever beam at a point a relatively short distance from said fulcrum point, so that increased tension upon the guy will tend to swing the outer end of the lever beam toward the second portion of the guy. Tension adjusting means are also provided for exerting a pull of a predetermined amount at a predetermined point along the outer end of said lever beam, said pull being in effect opposite in direction to the tension exerted by the said second portion of said guy, so that the moment of said pull acting through its relatively long lever arm will be in

effect opposite and equal to the moment of the tension on the guy acting through its relatively short lever arm. As the respective arm lengths are known, a definite tension may be applied to the guy by applying a determinable pull through the tension adjusting means aforesaid. This is effectuated by providing a tension adjusting tie member which extends from the first portion of the guy to a point along the outer end of the lever beam. Said tie member is arranged to be adjustable in effective length and it includes a suitable spring element of known value.

Thus, to obtain a desired tension upon the guy, a predetermined effective length of said tension adjusting tie member is joined to the outer end of the beam at a predetermined point thereof. The tension on the guy may then be increased until a predetermined position of balance of the lever beam is achieved, whereupon the desired tension will have been applied to the guy. Means are preferably also provided to then lock the device in said position of balance so that the delicate parts of the tension adjusting tie member may be removed.

In this specification there is described, and in the annexed drawings shown, what is at present considered a preferred embodiment of the present invention. It is, however, to be understood that said invention is not limited to said embodiment inasmuch as changes therein may be made without the exercise of invention and within the true spirit and scope of the claims hereto appended.

In said drawings,

35 Figure 1 is an elevational view of a tensiometer embodying the present invention in position in a guy, the parts being shown in their relaxed positions;

40 Figure 2 is a view similar to Figure 1, the parts being shown however after the tensiometer has been set for a particular guy tension and after said tension has been applied to the guy;

45 Figure 3 is a view similar to Figure 2, except that it is drawn to a larger scale and the locking tie rod has now been secured to the lever beam to lock the parts in place;

Figure 4 is a perspective view of the lower end of the tensiometer of Figure 3;

50 Figure 5 is a view of the outer end of the lever beam of Figure 3, taken along the line 5-5 thereof, with only the tension adjusting pin in place.

Referring now more particularly to the drawings, the tensiometer there illustrated includes a lever beam 14 which is actually made up of two separate, duplicate lever beam elements which are sustained in spaced opposed relationship by the other parts hereinafter described. Each of said lever beam elements comprises a

flat substantially triangular head 13, to one corner of which is suitably secured, as by welding, an elongated flat lever arm 15.

Each of said lever arms 15 is pierced by a plurality of holes 16 along its length, said holes being in register and receivable to a locking pin 17 and a tension adjusting trunnion pin 19. Each of the heads 13 is pierced by a fulcrum hole and an upper guy pivot hole. Each fulcrum hole is positioned at the corner of the head 13, furthest removed from the lever arm 15, and said holes are in register and are receivable to a fulcrum pivot pin 21. The upper guy pivot holes are also in register and are receivable to an upper guy pivot pin 23.

A clevis 25 is made up of two duplicate elongated clevis plates 27 which are sustained in spaced opposed relationship, each of which plates is pierced at one end by a clevis pivot hole and at the other end by a lower guy pivot hole. The clevis pivot holes are in register and are receivable to a clevis pivot pin 29 and the lower guy pivot holes are also in register and are receivable to a lower guy pivot pin 31.

The lower portion 33 of the guy, which extends up from a guy anchorage (not shown), terminates at its upper end in a guy terminal 35 which is pierced by a transverse pivot hole. Said guy terminal 35 is pivotally secured to the lower end of the clevis 25 by means of the lower guy pivot pin 31. The said terminal 35 is positioned between the clevis plates 27 and acts as a spacer therefor.

The upper portion 37 of the guy, which incorporates a suitable tensioning means (not shown), such as a turnbuckle, terminates at its lower end in a guy terminal 39, which is pierced by a transverse pivot hole. Said guy terminal 39 is pivotally secured to the lever beam 11 by means of the upper guy pivot pin 23, which extends through the upper guy pivot holes in the lever beam 11 and through the pivot hole in the said terminal 39. Said guy terminal 39 is positioned between the two elements of said lever beam 11 and acts as a spacer therefor.

Pivotally secured to the upper end of the clevis 25, by means of the clevis pivot pin 29, are three separate tie members; namely, a fulcrum tie rod 41, a tension adjusting tie member 43 and a locking tie rod 45.

The fulcrum tie rod 41 is made up of a metal rod 47 provided at its lower end with a head 49 pierced by a transverse pivot hole, receivable to the clevis pivot pin 29, and at its upper end with a head 51 having a transverse hole, receivable to the fulcrum pivot pin 21, by which it is pivotally secured to the lever beam 11.

The tension adjusting tie member 43 includes a helical tension spring 53, to the lower end of which is hooked a lower hook rod 55 which terminates in a head 57, pierced by a transverse pivot hole, which head 57 is bifurcated so as to allow it to straddle the head 49 at the lower end of the fulcrum tie rod 41, aforesaid. An upper hook rod 59, which is hooked into the upper end of the tension spring 53, is provided with an elongated threaded shank 61 which extends slidably through an orifice 63 in the tension adjusting trunnion pin 19. The shank 61 may be provided with scale markings (not shown) along its length. Said upper hook rod 59 is also provided, beyond the said trunnion pin 19, with a sleeve 65, which is slidable axially upon the said shank 61, and a knurled, internally threaded nut 67, which is in threadable engagement with

said shank beyond said sleeve. The upper end of the tension adjusting tie member 43 may be pivotally secured to the lever beam 11 at any one of a plurality of positions, depending upon the positioning of the tension adjusting trunnion pin 19. An annular thrust bearing 68 may be interposed between the trunnion pin 19 and the sleeve 65.

The locking tie rod 45 comprises a metal rod 69 provided at its lower end with a head 71, pierced by a transverse hole, receivable to the clevis pivot pin 29, and at its upper end with a head 73, similarly pierced by a transverse hole. Said head 71 is bifurcated so as to allow it to straddle the head 57 mentioned above. The head 73 may be secured to the lever arm 15 by means of the locking pin 17 (after the desired guy tension has been effected, as will hereinafter appear).

All of the pins 17, 21, 23, 29 and 31, referred to above, may be made up in any suitable manner, the form shown in the drawings having a solid metal body with a flat head at one end and a transversely disposed cotter pin hole at the other. Preferably, each of said pins 17, 21, 23, 29 and 31 is also provided with a washer which is positioned over its end before a cotter pin 76 is installed.

The tension adjusting trunnion pin 19, however, is made up of a central cylindrical body 77 and a pair of axially disposed trunnions 79. The body is provided with the transverse orifice 63, already mentioned, which is slidably receivable to the threaded shank 61 of the tension adjusting tie member 43, and the trunnions 79 are pierced by transverse holes receivable to cotter pins 76.

In the operation of the tensiometer just described, it is interposed between the two portions 33, 37 of the guy, as shown in the drawings, 40 the guy terminal 35 being pivotally secured to the clevis 25 by the lower guy pivot pin 31, and the guy terminal 39 being pivotally secured to the lever beam 11 by means of the upper guy pivot pin 23. When first installed, and before any adjustments have been made, the parts will 45 be as shown in Figure 1; the knurled nut 67 being at that time in a slackened off position and the upper end of the locking tie rod 45 being disconnected from the lever beam 11. The upper 50 end of the tension adjusting tie member 43 may be positioned, by means of the trunnion pin 19, at any one of the several holes 16 provided for it along the lever arm 15, depending upon the tension which is to be applied to the guy. As 55 shown in the drawings, it is positioned at the outermost of said holes 16 for an application where considerable tension is to be applied to the guy.

The next step is to position the nut 67 along 60 the threaded shank 61, according to scale markings (not shown) on said shank, or by using a separate scale, so as to position it according to a predetermined calculation (so that, when the operation is completed, a certain tension will have 65 been put upon the guy). The nut 67 may then be in the position on the shank 61 shown in Figures 2 and 3 and the lever arms 15 will make an acute angle with the axis of the guy. The next step is to take up the slack in the guy and exert tension upon it, by means of a turnbuckle (not shown) or other suitable means, until the lever arms 15 assume positions at right angles to the axis of the guy, as shown in Figures 2 and 3, at 70 which time the spring 53 will be suitably stretched 75 so that the moment acting in a clockwise direc-

tion, resulting from the spring tension thereof acting through the relatively long lever arm from the fulcrum pivot pin 21 to the trunnion pin 19 will equal the moment acting in a counterclockwise direction, resulting from the tension on the guy acting through the relatively short lever arm determined by the distance that the fulcrum pivot pin 21 is offset from the axis of the guy.

The locking tie rod 45 is of such a length that the hole through the head 73 at its upper end may be swung into register with the innermost pair of holes 16 on the lever arms 15 when the aforesaid state of balance has been achieved and the lever arms 15 are disposed normal to the guy axis. The upper end of the locking tie rod 45 may then be pinned to the lever beam 11 by means of the locking pin 17, whereupon the threaded hook rod 59, the nut 67 and the spring 53 may be removed for protection from the elements.

While there has been described what is at present considered a preferred embodiment of the invention, it will be obvious to those skilled in the art that various changes and modifications may be made therein without departing from the invention, and it is, therefore, aimed in the appended claims, to cover all such changes and modifications as fall within the true spirit and scope of the invention.

What is claimed is:

1. In a tensiometer for a guy, an elongated lever beam, a fulcrum near one end thereof, a first guy pivot spaced a short distance along said beam from said fulcrum, a tension adjusting pivot spaced a further distance along said beam, a clevis, a clevis pivot at one end of said clevis, a second guy pivot at the other end thereof, a fulcrum tie rod extending from the fulcrum to the clevis pivot, a tension adjusting tie member extending from the tension adjusting pivot to the clevis pivot, said tension adjusting tie member including a spring element and means to shorten the effective length of said member so as to adjust the amount of pull which may be exerted by it, means to secure two portions of the guy to the first and second guy pivots respectively.

2. In a tensiometer as defined in claim 1 above, a locking tie rod secured at one end to the clevis pivot and provided at its other end with means to secure it to the lever beam at a point offset from the fulcrum, and said locking tie rod being of a length to act as a gauge to indicate when the lever beam is positioned at a predetermined angle relative to the axis of the guy.

3. A tensiometer as defined in claim 1, including means to lock the lever beam in a predetermined position relative to the guy.

4. In a tensiometer to couple two spaced free ends of two portions of a guy together and enable a tension on said guy to be adjusted, a lever beam pierced by a plurality of holes along its length, said holes including a fulcrum pivot hole near one end of said lever beam, a guy pivot hole a relatively short distance from said fulcrum pivot hole, and a plurality of tension adjusting pivot holes further removed from said fulcrum pivot hole, a clevis pierced by two holes along its length, a fulcrum tie rod pierced by a hole at each end, a tension adjusting tie member comprising a hook rod provided with a hook at one end and pierced by a hole at the other end, a second hook rod provided with a hook at one end and a threaded shank at the other, a helical spring spanning said

hooks, and a nut threaded upon said shank, a terminal on each of the free ends of the guy, each such terminal being pierced by a hole, a plurality of pivot pins, one end of the fulcrum tie rod being pivotably secured to the lever beam at the fulcrum pivot hole by means of one of said pivot pins, one guy terminal being pivotably secured to the lever beam at the guy pivot hole by means of another of said pivot pins, the shank aforesaid of the tension adjusting tie member being pivotably and longitudinally adjustably secured to the lever beam at one of the tension adjusting pivot holes by means of another of said pivot pins, the other ends of the fulcrum tie rod and the tension adjusting tie member being pivotably secured to the clevis at one hole thereof by means of another of said pivot pins, and the other guy terminal being pivotably secured to the clevis at the other hole thereof by means of another of said pivot pins.

5. A tensiometer as defined in claim 4, including a locking tie rod, and means securing said locking tie rod to the lever beam at a point other than the fulcrum pivot hole thereof and to the clevis, at least one of said means being separable.

6. A tensiometer as defined in claim 4, including means to lock the lever beam at a fixed position relative to the guy.

7. In a tensiometer to couple two spaced free ends of two portions of a guy together and to adjust the tension on said guy, a lever beam provided with a fulcrum, a guy pivot positioned a relatively short lever distance from said fulcrum, and a tension adjusting pivot positioned a relatively large distance from said fulcrum, a fulcrum tie member, a tension adjusting tie member adapted to exert a predetermined pull, means to secure one end of the fulcrum tie member to the fulcrum of the lever beam, means to secure one of the free ends of the guy to the guy pivot of the lever beam, means to secure one end of the tension adjusting tie member to the tension adjusting pivot of the lever beam, and means to secure the other ends of the fulcrum tie member and of the tension adjusting tie member to the other free end of the guy.

8. In a tensiometer as defined in claim 7, a locking tie member and means securing one end of said locking tie member to the lever beam at a point removed from the fulcrum point thereof and means securing the other end of said locking tie member to the last mentioned free end of the guy, at least one of said securing means being separable.

9. A tensiometer as defined in claim 7, including means to lock the lever beam at a fixed position relative to the guy.
